US00D412751S

United States Patent [19]**Davis et al.****Patent Number: Des. 412,751****Date of Patent: ** Aug. 10, 1999**[54] **BACK WRAP HAVING THERMAL CELLS**

4,575,097 3/1986 Brannigan et al. 128/402

[75] Inventors: **Leane Kristine Davis**, Milford; **Ronald Dean Cramer**, Cincinnati, both of Ohio

(List continued on next page.)

[73] Assignee: **The Procter & Gamble Company**, Cincinnati, Ohio**FOREIGN PATENT DOCUMENTS**[**] Term: **14 Years**
